UNITED STATES PATENT OFFICE.

ETTORE BELLINI, OF ENGHEN-LES-BAINS, FRANCE.

APPARATUS FOR DIRECTED WIRELESS TELEGRAPHY AND TELEPHONY.

1,221,787.

Specification of Letters Patent.

Patented Apr. 3, 1917.

Application filed June 19, 1915. Serial No. 35,103.

To all whom it may concern:

Be it known that I, ETTORE BELLINI, subject of the King of Italy, residing at 49bis Boulevard Cotte, Enghien-les-Bains, Seine 5 and Oise, in the Republic of France, have invented new and useful Improvements in Apparatus for Directed Wireless Telegraphy and Telephony, of which the following is a specification.

10 This invention has for its object to provide wireless telegraph and telephone apparatus which allows, in regard to transmission, of controlling the direction of maximum projection of electromagnetic waves, 15 without turning the antennæ, and in regard to reception of making adjustment for reception from selected directions and ascertaining the direction of the transmitting station, also without moving the antennæ. 20 The apparatus essentially comprises pairs of fixed conductive plates arranged around an axis, diametrically opposite each other, the number of pairs being equal to the number 25 of aerials for directed waves, and the two opposed plates of each pair being connected to one of the aerials. Opposite the fixed conductive plates are arranged rotatable conductive plates directly or indirectly connected to high frequency apparatus such as 30 a sparking device, an arc, an alternator or a detector. These rotatable plates are mechanically connected to each other and can be rotated about the axis of the fixed system, 35 so that they can be placed opposite the two plates of any of the fixed pairs, or in any intermediate position. The fixed conductive plates and the movable conductive plates are arranged respectively in parallel planes, a 40 short distance apart. The movable plates are preferably given special shapes, as will be described hereinafter.

The invention is illustrated in the annexed drawings, given as an example.

45 Figure 1 shows one form of construction of the apparatus, and

Fig. 2 a modification thereof.

The apparatus shown in Fig. 1 comprises two pairs of conductive metal plates *a a*, 50 *b b* arranged in one plane, the plates belonging to each pair being diametrically opposite each other. These plates are in the form of quadrants, and almost entirely cover a circular surface having approximately the radius of the quadrants; between them is left only sufficient space for insulation. The

two diametrically opposed sectors *a a* are connected to an aerial 1 for directed waves, and the two sectors *b b* are connected to a similar aerial 2 perpendicular to the aerial 60 1. Each of these aerials may be formed in the well known manner either by a couple of vertical antennæ, or by a frame, or by any type of directed wave aerial which radiates and receives with the maximum intensity in its own plane. 65

Above or below the fixed sectors *a b* there is a rotary system consisting of two circular plates *c* mechanically connected together, but insulated from each other. Instead of circular plates I may however use two square plates having their homologous sides parallel, or two quadrants or the like. These two plates *c* do not extend at any point beyond the circle formed by the four sectors, *a b*. They are arranged to rotate about the axis *o* perpendicular to the plane of the drawing, and are connected, in the example shown, by conductors *f g* to an oscillatory circuit comprising a condenser *d*; *h* designates the terminals of the spark gap device and *i* the inductance in the primary circuit of a transmitting station. 75 80

With this device, when the line *M—N* 85 which represents the greatest dimension of the rotary system, coincides with one of the directions *A—A*, *B—B*, *C—C* or *D—D* the intensity obtained in transmission is greatest in the direction *M—N*. If the line *M—N* 90 occupies an intermediate position, coinciding for example with the direction *F—F*, the direction of maximum intensity makes with the line *M—N* a definite angle which can easily be determined. It will, therefore, 95 be understood that with a device of this kind, and with the aid of a suitably prepared correcting table, adjustment can be made for transmission in any desired direction. All that is required is to rotate the 100 movable system in such a manner that its line *M—N* lies in the required direction, if the latter is the direction *A—A*, *B—B*, *C—C* or *D—D* or makes with the required direction an angle given by the table. Similarly in the case of a receiving station, to 105 find the direction of a transmitting station all that is required is to rotate the movable system till the intensity attains its maximum, the direction required being that of 110 the line *M—N* or making a certain angle with that line.

A convenient arrangement is to give the plates of the movable system an outline determined by a line given by the equation

$$5 \quad \rho = \rho_0 \sqrt{\cos. \alpha}$$

(Fig. 2) with $\cos. \alpha$ always positive. In this equation ρ is a radius vector ρ_0 is the radius vector maximum OM or ON and α is the angle between these two radii vectors. In 10 this case, the direction of maximum intensity always coincides with the line M—N of the movable system, and the value of the maximum intensity is constant.

Instead of using two aerials at 90° to each 15 other, I may, of course, use three aerials at 60° , or generally speaking n aerials at $180^\circ / n$ the number of pairs of fixed sectors varying 20 accordingly. The movable system of the apparatus may be made to act upon the aerials in any convenient known manner, the arrangement shown being merely given as an example in the case of a transmitter. A plurality of systems of fixed and movable plates 25 may be superposed in order to increase the capacity of the apparatus.

Having now described my invention, what I claim as new and desire to secure by Letters Patent is:

30 1. An apparatus for directed wireless telegraphy or telephony comprising in combination aerials for the reception or transmission of directed waves, fixed conductive plates arranged about an axis, diametrically 35 opposite each other in pairs, the number of pairs being equal to the number of directed aerials, and the two plates of each pair being connected to one of the aerials,—a rotary

system of conductive plates mechanically 40 connected together and adapted to rotate about the axis of the fixed system,—and a high frequency apparatus to which the rotary system of conductive plates is connected, substantially as described and for the 45 purpose set forth.

2. An apparatus for directed wireless telegraphy or telephony comprising in combination aerials for the reception or transmission of directed waves,—fixed conductive 50 plates arranged about an axis in a plane,—diametrically opposite each other in pairs, the number of pairs being equal to the number of aerials, and the two plates of each pair being connected to one of the aerials,— 55 a rotary system of conductive plates parallel to the fixed plates and mechanically connected together, said system rotating about the axis of the fixed system and the outline of the said movable plates being given by the 60 equation

$$\rho = \rho_0 \sqrt{\cos. \alpha}$$

with $\cos. \alpha$ positive, ρ being a radius vector, ρ_0 the radius vector maximum and α the angle between these two radii vectors,—and a high frequency apparatus to which the rotary system of conductive plates is connected, substantially as described and for the 65 purpose set forth.

In testimony whereof I have signed my name to this specification in the presence of two subscribing witnesses.

ETTORE BELLINI.
